DESIGN FOR A FINGER RING

Arthur C. Braun, Maplewood, N. J.

Application January 25, 1941, Serial No. 98,380

Term of patent 7 years

To all whom it may concern:

Be it known that I, Arthur C. Braun, a citizen of the United States and a resident of Maplewood, in the county of Essex and State of New Jersey, have invented a new, original, and ornamental Design for a Finger Ring, of which the following is a specification, reference being had to the accompanying drawing, forming part thereof.

I claim:

The ornamental design for a finger ring, as shown.

ARTHUR C. BRAUN.
